MAILABLE MATTER OF ENVELOPES

Filed June 18, 1924

2 Sheets-Sheet 2

Inventor.
Stella Benenato

UNITED STATES PATENT OFFICE.

STELLA BENENATO, OF PHOENIX, ARIZONA.

MAILABLE MATTER OF ENVELOPES.

Application filed June 18, 1924. Serial No. 720,881.

This invention relates to connecting means for mailable matter, such as envelopes, paper receptacles, postal cards, wrappers and the like.

5 An object of this invention is to provide an improved means of temporarily connecting mailable matter over that shown in my issued United States Patent numbered 1,453,616, and especially to provide against the accidental breaking of the connecting means and the consequent separation of the joined articles, and to provide a connecting means which is integral with the articles to be connected and which may be quickly, simply and 10 easily formed in the making of the articles themselves, and whereby the articles may be stamped by dies in integral form including the connecting means.

A further object of this invention is to provide a means whereby the gummed portions of the top flaps may be subsequently damped and the envelopes sealed in one operation without possible interference of sticking or gumming to the adjacent envelope, and in 20 which each of the top flaps is provided with an extra outer edge ungummed and which in overlapping relation may be temporarily connected with the top flaps extended upward or downward.

30 A further object of this invention is to provide for the arrangement of the envelopes in boxes and removably connecting together any given or desired number, making insertions into and stamping the envelopes before they 35 are separated, and drawing the same into a typewriter automatically by rotation of the platen or insertion from an open or opening in a box.

With the foregoing and other objects in 40 view I have invented the device shown in the accompanying drawings, in which:

Figure 1 is a front elevation of a series of envelopes connected together in accord with my invention,

45 Figure 2 is a rear elevation of the showing in Figure 1;

Figure 3 is a perspective of the showing in Figure 2, with the flaps in different positions;

Figure 4 is a section at 4—4 of Figure 2;

50 Figure 5 is a section at 5—5 of Figure 7;

Figure 6 is a blank from which one of the envelopes shown in Figs. 1, 2, 3 and 4 is made;

Figure 7 is a plurality of envelopes of modified form, connected; and

Figure 8 is a blank from which the modification shown in Figure 7 is made.

Like reference characters indicate like parts throughout the several views and in the specification, in which, referring to Figure 6, I provide an envelope blank 2, having 60 side flaps 3 and 4, a top flap 5, a bottom flap 6, and tongues 7 and 8, extending from the flaps 6. The tongues 7 and 8 are adapted to bend upon the dotted line 9 and also in alinement with the edge 10 of the flap 6, so that as shown 65 particularly in Figure 3, the flap 6 upon being bent upon the line 11, with the flaps 3 and 4 bent over and sealing the flap in the form of an envelope, the tongues 7 and 8 bent upon the edge 10 of the flap 2 and being 70 gummed on the under side, are adhesively connected to the under side of the flap 2 as far as the dotted line 9, leaving an adhesive flap between the dotted line 9 and the distant end of the tongue 8, whereby the envelope is connected to the succeeding envelope. The flap 5 is provided with a gummed area 12, and a 75 nonadhesive area 13; the area 13 adapted to overlap the succeeding flap 5 on the next envelope and serve as a shield or protection, but 80 being ungummed so that it will not adhere to the next envelope and will only seal on the portion contacting the envelope to which the flap belongs.

It is obvious in the operation of these envelopes that they are integrally joined together so that they form a substantially continuous sheet, whereby a typist may without interchanging envelopes after the addressing of each one continuously address the envelopes; and, further, whereby with a sponge or other suitable means run over the under side of the sheet, the whole may be moistened for sealing and sealed within a short time.

In the modification shown in Figures 7 and 8, I provide the set of flaps 2^a, 3^a, 4^a and 5^a, functioning similar respectively to the flaps 2, 3, 4 and 5; and upon the flap 4^a I provide a lower gummed surface 14, and also provide at its terminal a tongue 15, the tongue 15 provided at its lower edge with a secondary tongue 16, being provided with an adhesive, 17, and the tongue 15 being provided with an angular tertiary tongue 18.

In closing the envelope, the tongues 2^a, 3^a and 4^a are folded over in the usual manner, with the tertiary tongue 18 underlapping the tongue 3^a, and with the tongue 16 extending as shown in Figure 7, and its gummed surface adhesively connected to the flap 5^a of the next succeeding envelope. The tongue 16 is preferably perforated at its root, as at 19, whereby the envelopes may be easily disconnected 10 when desired.

Claims:

1. An envelope consisting of a blank having a flap extending at the side of the blank, the side flap provided with a pair of tongue-like 15 extensions, a secondary flap adapted to cooperate with the first flap, one of the tongue-like extensions adapted to engage the secondary flap, and the other tongue-like extension adapted to be adhesively connected to a sec- 20 ondary envelope.

2. An envelope including a body member and a plurality of flaps struck out from a single sheet in the form of a unitary structure, one of said flaps having a plurality of tongues projecting from one edge thereof to provide 25 for the securing thereto of another envelope, one of said tongues being gummed on one side for securing the envelope to another and perforated to facilitate detachment of one envelope from another, said envelope including 30 a sealing flap adapted to overlie said tongues when in sealed position and having its free edge ungummed and adapted to overlie said securing tongue beyond its perforated point to permit the detachment of the tongue along 35 said perforations.

In testimony whereof I have hereunto affixed my signature.

STELLA BENENATO.
